(57) **CLAIM**

The ornamental design for a light emitting display module with diffusely reflective facade, as shown and described.

DESCRIPTION

FIG. 1 is a perspective view of a light emitting display module with diffusely reflective facade showing the design, oblique lines on the front view indicating a reflective surface;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines of FIG. 1 through FIG. 7 indicate unclaimed portions of the design.

1 Claim, 5 Drawing Sheets
